UNITED STATES PATENT OFFICE.

DANIEL ARGERBRIGHT, OF TROY, OHIO.

ROAD-CART.

SPECIFICATION forming part of Letters Patent No. 298,652, dated May 13, 1884.

Application filed September 17, 1883. (No model.)

To all whom it may concern:

Be it known that I, D. ARGERBRIGHT, a citizen of the United States, residing at Troy, in the county of Miami and State of Ohio, have 5 invented certain new and useful Improvements in Two-Wheeled Carts; and I do declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 of the drawings is a representation 15 of a plan view of my two-wheeled cart. Fig. 2 is a vertical longitudinal sectional view, and Figs. 3, 4, and 5 are detail views.

This invention has relation to road-carts; and it consists in the construction and novel 20 arrangement of devices, as will be hereinafter fully described, and particularly pointed out in the claims appended.

Referring by letter to the accompanying drawings, *a* designates the axle, mounted on two 25 wheels. This axle may be either a straight axle or a crank-axle. I prefer the crank-axle shown, for the reason that I can hang the body down lower by using it. I also weld the spring-supports *b b* for the lower springs, *cc*, onto the 30 axle, as by so doing the axle is not weakened by bolt-holes, and the expense of clips is avoided. The springs I term "double-springs," and are semi-elliptic. The lower springs, *cc*, are bolted to the spring-supports *b b* by bolts 35 *d d*.

e e designate the upper and intermediate springs, to which the side bars, *ff*, are bolted. The upper and lower springs are connected in pairs at their rear ends by wrist-bolts *gg*, having washers *hh*, intermediate of their ends, made 40 solid with the bolts, and the ends of the bolts that enter the eyes of the lower springs, *cc*, are made tight in the spring ends, and the nuts *i* on the outer ends of said bolts *gg* are screwed up solid. The inner ends of the bolts to which 45 the upper springs are attached form wrists upon which the upper springs have free play. I may, however, use a connecting-rod at these points, as shown at the front ends of the springs, 50 instead of the bolts; but the bolts, where some styles of body are used, present a better appearance than the rod would at this point. The

front ends of the upper and lower springs are hinged to a connecting-rod, *k*, washers *h' h'* being interposed between the eyes at the ends of 55 the springs, and securing-nuts *i'* are employed at the ends of the rod.

Another feature of the invention is a safety-link, *l*, with a joint, or slotted without a joint. One end of this jointed or slotted link *l* is perforated and secured to the end of a lateral arm, *m*, secured to the thills near the front ends of 60 the pairs of springs, and held in pivotal connection with the lateral arms by a nut, *n*. Where a jointed link is used, the end of the 65 other arm of the link is perforated and secured to the end of the connecting-rod *k* by a nut, *i'*, also in pivotal connection with the rod *k*. Where a straight link is used, the end connecting 70 with the rod *k* is slotted to give the necessary play to the rod. The object of the link *l* is to prevent the body from falling backward or forward in case the spring-supports should break where attached to the axle, which is liable to take place where there is no other attachment to the axle. 75

The manner of connecting the springs by the wrist-bolts and connecting-rod, or by two connecting-rods, does away with the loose shackles commonly employed, and at the same time 80 binds the springs more firmly together.

The side bars, *ff*, are connected by metal straps *oo*, having transverse slots *pp* near each end. The body of the road-cart rests on these 85 metal straps *oo*, and is secured thereto by passing bolts *qq* down through the body-sills and through the slots, and turning nuts on the bolts up against the straps. By slackening the nuts under the straps, the body may be adjusted either forward or backward, to get a perfect 90 balance of the cart.

To secure the shafts *r* to the axle, I first place on the axle the shackles *ss*, and secure them rigidly to the axle by the cross-ties *s' s'* and bolts *tt*. I then place the shafts on the shackles, 95 the shaft-irons *u* having projections *u'*, which pass down into the lips of the shackles, which project upward. The projections and lips are perforated for the securing-bolts *u''*, which are passed through to form hinges. The object of 100 the hinges is to allow the shafts to be adjusted up or down to suit either a large or a small horse, without throwing the body out of level. This adjustment is accomplished in the follow-

ing manner: To raise the shafts at their points, slack the front nuts, *v*, and screw up the rear nuts, *v'*, on the bolts connecting the shafts to the shackles. To lower the points of the shafts, slack the rear nuts and screw up the front nuts, and when the nuts have been screwed up tight the shafts are rigidly secured to the axle. The shafts are spliced in front of the cross-bar by means of sockets *w w*. The ends of the shafts *10* sections are made tapering, and they rest in the tapering seats of the sockets and are secured in place by bolts *x x*. The advantages of the splices are that the cart may be reduced more than one-half in length for shipping, thus putting them in more compact form, whereby more carts can be put on a car, thus reducing the freight. Should the shaft get broken in front of the splice, it may be more cheaply replaced, and can be done at any carriage or wagon shop.

Having thus fully described my invention, what I claim as new, and desire to secure by Letters Patent, is—

1. In a road-cart, the double semi-elliptic springs secured directly to the axle and the *25* side bars, and connected in pairs at their rear

ends by wrist-bolts, washers, and securing-nuts, and at their front ends by a connecting-rod, washer, and securing end nuts, substantially as specified.

2. In a road-cart, the combination, with the *30* connecting-rod *h* at the frontends of the springs, of the link *l*, connecting the lateral arm *m* on the inside of one of the shafts, to prevent the body from tilting backward or forward in case of the breakage of the axle-connection with *35* the springs, substantially as specified.

3. The combination, with the semi-elliptic *40* springs connected to the axle and at their front and rear ends, as described, of the side bars and connecting-bars *o o*, provided with the transverse slots *p*, whereby the cart-body may be secured thereto by bolts and nuts, and adjusted back and forth, substantially as and for the purposes specified.

In testimony whereof I affix my signature in presence of two witnesses.

D. ARGERBRIGHT.
